United States Patent Office

Des. 231,042

Patented Mar. 26, 1974

231,042

CARRYING BAG

Robert M. Lee, New York, N.Y., assignor to Hunting
World, Incorporated, New York, N.Y.

Filed Jan. 10, 1972, Ser. No. 216,866

Term of patent 14 years

Int. Cl. D3—01

U.S. Cl. D87—5 G

FIG. 1.

FIG. 2.

FIG. 3.

FIG. 4.

FIG. 1 is a side perspective view of a carrying bag showing my new design;

FIG. 2 is a perspective view of the other side thereof;

FIG. 3 is an end perspective view of the carrying bag when in collapsed position; and

FIG. 4 is a perspective view of the other side thereof.

I claim:

The ornamental design for a carrying bag, as shown.
